UNITED STATES PATENT OFFICE.

WILLIAM GOLDIE, OF WILKINSBURG, PENNSYLVANIA.

REINFORCING-BAR FOR CONCRETE CONSTRUCTION.

1,272,422.

Specification of Letters Patent. Patented July 16, 1918.

Application filed July 16, 1917. Serial No. 180,768.

To all whom it may concern:

Be it known that I, WILLIAM GOLDIE, a citizen of the United States, and resident of Wilkinsburg, in the county of Allegheny and 5 State of Pennsylvania, have invented a new and useful Improvement in Reinforcing-Bars for Concrete Construction; and I do hereby declare the following to be a full, clear, and exact description thereof.

10 My invention relates to reinforcing-bars for concrete construction, its object being to provide a strong and light bar having large exposure of surface to the concrete and providing means for anchoring the bar within 15 the concrete in such way that the bar reinforces and anchors the concrete and the concrete reinforces and anchors the bar.

It comprises, generally stated, a reinforcing-bar for concrete construction formed of 20 a twisted I-shaped bar, *i. e.* a bar having a central web portion with widened or thickened rib portions at each edge of the web. It also comprises other improvements as hereinafter set forth.

25 Figure 1 is a side view of a bar embodying the invention; Fig. 2 is a cross-section of the same. Fig. 3 is a longitudinal central section of the same; Fig. 4 shows the bar embedded in the concrete; Fig. 5 a cross-section of the bar as so embedded; Fig. 6 a perspective view of the bar before twisting; Fig. 7 a like perspective view of a modified form thereof; and Fig. 8 a view of this modified form twisted to form 35 the reinforcing-bar.

The reinforcing-bar 2 is formed of any suitable structural shape having a central web portion, *for example*, an I-bar, such as shown at 3, Fig. 6, having a web portion 4 and flange portions 5. This rolled bar is twisted either when hot or cold to form the reinforcing-bar, such as illustrated in Fig. 1, in which case the web portion forms the spiral central portion 6, while the flanges provide 45 spiral convolutions 7 extending around the same, so providing a bar of great strength and relative lightness, having pockets 8 for the reception of the concrete so that the concrete maintains a strong hold upon the body 50 of the bar.

I prefer the structural bar of general I-shape because the flanges extend on opposite sides of the web, and so form a spiral depressed pocket for the reception of the concrete within the circumference of the spiral bar. Such construction gives pockets 8,

which extend under the ribs or flanges 7 and form undercut pockets, and the concrete flows into these pockets and fills out under the ribs or flanges 7 and so under the convolutions of the flanges, so uniting the body of the concrete directly to the twisted bar. The spiral tongue portions 9 of the concrete thus formed act as braces between the adjoining spirals of the bar and act to sustain 60 the compression strains between the spiral webs and flanges, filling the undercut pockets 10 extending under the flanges 7, and the continuous spiral tongues 9 of concrete are thus bound within the twisted bar and in 65 addition to anchoring the concrete to the bar, sustains all strains which might cause yielding of the bar itself. To this end, while I prefer that the corners of the flange portions 7 of the twisted bar shall be rounded, 70 I prefer that the junction between the flanges and the web portion shall, if possible, be made angular, as illustrated, to better sustain the compression strains developed.

The twisted structural bar is made proportionately light as compared with a solid bar or a bar having a thick central portion. The thin web is braced spirally around its circumference by means of the flange portions and the twisted web 8, plus the spirally-laid 80 flange portions 7, giving a very strong, light structure adapted to resist strains in all directions,—first, through the twisting of the web portion; and next, through the spirally-laid flange portions, which, where the web 85 portion is approximately vertical, is adapted to sustain heavy loads, while where the web is approximately horizontal, the spirally-laid flange portions are approximately vertical and are laid in such way as to sustain 90 under tension from the highest and lowest parts of the bar all vertical strains and distribute them throughout the spiral flange portion of the structure. The reinforcing bar is thus adapted to sustain much heavier 100 loads than the same amount of metal in an ordinary solid bar, and because of the greater diameter and surface exposure, it obtains a much stronger hold upon the concrete.

105 As illustrated in Fig. 4, the concrete itself by its spiral tongues fitting between two adjoining spiral flanges largely increases the strength of the beam or bar, sustaining the compression strain by reason of the concrete held between the same in the spiral recesses, as above described. The spirally-

110

extending flanges are thus braced by the concrete, which, by the filling of the concrete, provides approximately the strength of a metal bar of the full diameter of the 5 twisted bar or even greater strength. The flanges and web fully sustain the tension strains, and the load from tension to compression changes so gradually that where portions of the bar are under tension, other 10 portions sustain it under such strain,—and where like portions are under compression, these strains are carried in the same way through the spiral lay both of the web and the flange portions. At the same time, the 15 flanges extending over the pockets form practically dove-tailed seats, holding the concrete confined within them,—where an I-shaped bar is used, and there is large exposure of the metal surface for holding of 20 the concrete thereto.

Thus the reinforcing-bar provides in itself a spiral structure shaped to sustain and distribute the vertical or other strains coming upon the bar, and especially to sustain the 25 tension strain while the filling of concrete provides a continuous spiral tongue fitting within the reinforcing-bar, firmly uniting the concrete to the bar and sustaining all compression strains brought upon the bar, 30 so utilizing the concrete itself for bracing the spiral bar against compression strain. As shown in Figs. 1, 3 and 4, where the I-bar has flat outer faces, the twisting of the bar when cold provides the dish-shaped 35 outer faces 12 following the surface of the spiral convolutions, and these depressed faces also act to hold the concrete in place.

In Figs. 7 and 8, I have shown the beam with its web 15 and flanged heads 16 and 40 central ribs 17 extending out beyond the heads.

The character of the twisted reinforcing-bar formed from the bar is shown in Fig. 8 where the combined web and enlargements 45 provide a very strong reinforcing structure. The shape and character of the flange or head portion, the thickness of the web, etc., may, of course, be varied as found desirable. The invention is intended to cover

any character of twisted metal web structure having enlarged ends of flange or other form. 50

What I claim is:

1. A reinforcing-bar for concrete construction formed of a twisted bar having a 55 central web portion and enlargements beyond the web.

2. A reinforcing-bar for concrete construction formed of a twisted bar having a central web portion with widened rib portions at the edges of the web. 60

3. A reinforcing-bar for concrete construction formed of a twisted I-shaped bar.

4. A reinforcing-bar for concrete construction formed of a twisted bar having a 65 central rib portion of uniform section and outstanding flange sections beyond the rib portions, said flanges being of uniform section.

5. In reinforced concrete construction, the 70 combination of a twisted bar having a sectional web portion and enlarged heads, and a filling of concrete surrounding the beam and entering within the spiral pockets between the enlarged heads. 75

6. A reinforcing bar for concrete construction formed of a twisted bar having a central web portion and enlargements beyond the web, the web and enlargements being connected by an angular joint. 80

7. A reinforcing-bar for concrete construction formed of a twisted I-shaped bar, the outer faces of the convolutions so produced being concave.

8. A reinforcing bar for concrete construction formed of a twisted bar having a central web portion and lateral extensions beyond the web. 85

9. A reinforcing bar for concrete construction formed of a twisted bar having a central web portion, and laterally extending edge portions. 90

In testimony whereof, I the said WILLIAM GOLDIE, have hereunto set my hand.

WILLIAM GOLDIE.
